UNITED STATES PATENT OFFICE.

JOHAN LUDVIG KIHLOVIST, OF ADELSÖ, EKERÖ, NEAR STOCKHOLM, AND GUSTAF LINDÉN, OF NÄSSJÖ, SWEDEN.

KNITTING-MACHINE.

1,112,456.

Specification of Letters Patent.

Patented Oct. 6, 1914.

Application filed September 30, 1911. Serial No. 652,161.

To all whom it may concern:

Be it known that we, JOHAN LUDVIG KIHLOVIST and GUSTAF LINDÉN, subjects of the King of Sweden, residing, respectively, 5 at Adelsö, Ekerö, near Stockholm, in the Kingdom of Sweden, and at Nässjö, in the District of Jönköping, in the Kingdom of Sweden, have invented new and useful Improvements in Knitting-Machines, of which 10 the following is a specification, reference being had to the drawings accompanying and forming a part hereof.

It is well known that knitting-machines are adapted to be used for making several 15 articles especially underwear and other articles of clothing which are of great importance for home and for daily use. A knitting-machine is, therefore, an implement which should be equally general in 20 use as for instance the sewing machine. This is, however, not the case. The reason for this seems to be that the knitting-machines are too complicated in construction and on account thereof too expensive, so 25 that the public in general cannot procure them. It is true that a knitting-machine of the well known type is very perfect in respect to capacity of producing articles of clothing of all kinds, but for knitting hose 30 and stockings or other simple articles generally used it is unnecessarily complicated and, on account thereof, unnecessarily expensive.

The object of the invention is to provide 35 a knitting-machine especially adapted for knitting hose and similar things and which is extremely simple in construction so as to represent a price making it possible for most people to procure the same.

40 The invention consists, chiefly, in this that the needles are placed with their hooks outward in radial or substantially radial directions in a suitable horizontal circular bed along the periphery of which the yarn-guide 45 is movable in one or both directions.

The invention further comprises the construction and combination of parts herein-after set forth.

In the drawings, we have shown a knitting-machine embodying the invention.

Figure 1 is a vertical section of the machine. Fig. 2 is a top plan view of the same. Fig. 3 is a bottom plan view of the upper plate detached. Fig. 4 is a top plan view of the needle bed. Fig. 5 is a bottom plan view of a modified form of the upper plate. Fig. 6 is a vertical section of a modified form of the machine.

Referring to the drawings, the needle bed consists of a lower stationary dial or disk 1 suitably circular in shape and provided at its upper side, near its circumference, with grooves for the needles, as shown in Fig. 4. Placed on the said disk 1 is an upper circular disk 2 adapted to turn in either direction about a pivot pin 3 (Fig. 1) projecting from the disk 1. The disk 2 carries the yarn-guide with the yarn-engaging spring devices 9 and 10 and the operating members or cams for the needles. The lower disk 1 is carried by a standard suitably formed by two tubes 4 and 5 one placed within the other so that the standard may be extended or reduced in length according to the length of the work. The inner tube 4 may be clamped in the outer one 5 by means of a set screw 6 screwed into a sleeve 7 and acting to compress the outer tube 5 against the inner one. The yarn passes from a reel 8 placed in the foot of the standard, as shown in Fig. 1, through the hollow standard and the hollow pivot pin 3, thence through a spring hook 9 attached to or formed by an arm 51 attached to the operating arm or crank 12, farther through 80 an eye at the outer end of a spring arm 10, likewise attached to the operating arm 12, thence through an opening 11 in the arm 12 and finally through the yarn-guide 13 placed at the outer end of the arm 12 85 through which it passes from above downward. The crank arm 12 is adapted to turn a certain distance relatively to the disk 2, said distance being limited by stops 14 at the upper side of the said disk. 95

Placed at the lower side of the disk 2 are the operating members for the needles 15. These parts consist, chiefly, of two fixed operating cams 17 projecting from the lower side of the disk 2 and a triangular 100 operating cam 16 movable in a radial direction between the fixed cams and having its inner straight edges parallel to the adjacent edges of the fixed cams so that the cams will form between them an angular 105 groove of a variable width (see Fig. 3). The butts 18 of the needles 15 project above the needle bed formed by the disk 1, as

clearly shown in Fig. 1. When the needle butts are in the path *a—b* indicated by dashed and dotted lines in Fig. 3, the needles are in operative or working positions, the outer edges of the cams 17 lying just in line with the said path. The outer parts of the triangular cam 16 cross the said path so that one or the other side of the said cam strikes the needle butts and moves the needles inward in the angular groove between the cams. The size of the loops formed *i. e.* fineness of the knitted fabric is dependent on the position of cam 16 relatively to the cams 17, the loops being longer as the cam 16 is moved toward the cams 17.

Projecting from the cam 16 into a radial slot 20 (Fig. 3) in the disk 2 is a suitable square sliding member 19 guided in the slot 20 during the adjustment of the cam. The sliding member 19 is pivotally connected to a link 21 the other end of which is connected to a lever 23 adapted to swing about a pivot pin 22, the free end of said lever forming a hand or pointer movable along a scale 24. The loop size may thus be easily adjusted.

If it be desired to bring all the needles out of operative position this may be easily effected by moving the cam 16 close onto the cams 17. In this position of the cam 16 the arc-shaped outer edge of the cam forms a continuation of the outer edges of the cams 17 as indicated by dashed and dotted line 27 in Fig. 3. The cam 16 is thus entirely inside the circle formed by the needle heads so that the needles will not be actuated.

When the needles are moved outward, they are liable to move by inertia beyond the outer edge of the cam 16 in case no means are provided for retaining them in operative positions. To this end guard cams or abutments 25 for the needle butts are provided outside the ends of the angular groove. It is easily seen that these abutments do not prevent the needle butts from entering the said groove.

As shown in Fig. 3, the lower side of the disk 2 leaves a free space for the needles which extends from the circumference of the disk up to an extension 26 at the center of the same, except at the place occupied by the cams and at the diametrically opposite part of the disk. The needles may therefore be freely moved by hand inward or outward. This considerably simplifies the change of needles to be operated. Thus if certain needles are to be brought out of action they may be simply pulled outward by hand into positions in which their butts lie in the path indicated by the dashed and dotted line *c—d* in Fig. 3. In this position of the needles the needle butts bear on a flange 28 projecting downwardly at the edge of the disk 2, in which position the needles are outside the path of the cam 16 so as to remain inactive.

When the needles are to be again thrown into operation they need only be moved inward by hand into positions in which they are reached by the cams.

If the needles are pushed inward by hand into positions in which their outer ends are entirely inside the circumference of the disks, the needle heads will be moved by the inner sides of the cams 17 into the path indicated by the dashed and dotted line *e—f* (Fig. 3), by which the needles are placed in inoperative positions. In order to again place the needles in operative positions two guiding tongues 29 are provided one or the other of which may be thrown into action according as the disk is rotated in one or the other direction. When the needles are in inoperative positions, the tongues 29 are placed close up to the central extension 30 of the disk. If the needles are to be projected into working position, one of the tongues 29 is swung outward into the position shown by dashed and dotted lines in Fig. 3. In this position the tongue acts on the inner ends of the needles so as to move the needle butts into positions in which they are caught by the outer side of a crescent-like part 31 projecting from the disk 2 and moved back into the path *a—b*. The swinging of the guiding tongues 29 is effected by handles 32 placed at the upper side of the disk 2 and adapted to be locked in positions by any suitable means (not shown).

When the needles are in their inward inoperative positions, the needle butts are inside the inner ends of the grooves in the needle bed. In moving the needles outward they must therefore be actuated in such a manner that they will not be brought into oblique positions in which the butts extend at an angle to the grooves so that the needles cannot be introduced into the same. This is secured by causing the tongues 29 to act directly on the ends of the needles so as to press on the needles in line with their shanks so as not to induce any turning movement of the shanks in the grooves in their longitudinal directions.

The flange 28 is shown cut away at two places 34 near the cam 16 and at opposite sides of its vertical plane of symmetry, and through the said openings the loops of the yarn are drawn in and out. When the needles are placed in the manner hereinbefore described in their outer inoperative positions they must be prevented from dropping through the openings 34. To this end an arc 35, suitably of angle-iron, is placed outside the openings 34, said arc having an upwardly projecting flange 36 extending at a distance from the edge of the disk 2 corresponding to the lengths of those parts of the needles which are outside the disk 2 when the needles are in the outer inoperative positions. The arc 36 is suitably supported by

the raised parts 14 of the disk 2 serving as steps for the arm 12. Placed at the ends of the arc are jaws 37 adapted to catch the outer ends of the outwardly moved needles and cause the same to enter upon the arc. 5 The outer ends of the needles then bear on the flange 36 of the arc and the needles are thus prevented from dropping.

In the modified form of the disk 2 shown 10 in Fig. 5 the disk is not open at its lower side so as to allow the needles to freely move inward and outward but instead thereof the disk has a number of grooves through which the needles may be moved from operative 15 into inoperative positions or vice versa. In the embodiment shown the disk 2 has a working groove 38, and at both sides of the same are grooves 39 and 40 concentric with the former. Placed between the grooves 20 38 and 39 is a guiding tongue 41, and placed in the groove 40 is a further guiding tongue 50. When the needles are working, the guiding tongue 41 is placed across the outer groove 39. If they are to be moved outward 25 into inoperative positions, the guiding tongue 41 is placed across the groove 38 so as to cause the needles to move outward into the groove 39. If the needles are to be moved inward from the groove 38 into inoperative 30 positions, this may be effected by hand after placing the disk 2 in a position in which the needles to be brought out of operation are just opposite one of the obliquely extending grooves 42 connecting the grooves 38 and 40.

As long as the needle heads are to be retained in the groove 40 the guiding tongue 50 takes up the position shown by full lines. If, on the contrary, the guiding tongue is 40 swung outward into the position shown by dashed and dotted lines, the needle butts are caught and moved outward through the transverse groove 42 into the working groove 38.

45 Fig. 6 shows merely schematically a modified form of the frame in which the operating crank 43 is placed at the foot of the standard and connected through gearing 49 to a hollow shaft 45 extending 50 through the standard and carrying the disk 2. The yarn from the reel 8 passes through the hollow shaft and thence in the manner hereinbefore described to the yarn-guide 13. The part carrying the reel 8 is shown connected 55 to the shaft 45 so as to rotate with the same, by which twisting of the yarn is prevented.

We claim:

1. In a knitting-machine, the combination 60 of an annular needle bed having an opening for the yarn inside the needle bed, hooked needles placed in the said bed, with their hooks directed outward, yarn-supplying means placed below the needle bed, yarn-guiding means placed above the needle bed, 65 and operating cams for the needles arranged so as to allow the needles to be moved by hand to an outer inoperative and an inner inoperative position independent of said needle operating cams, part of said cams, including an adjustable element, being adapted to move the needles to an intermediate operative position when said element is properly adjusted. 70

2. In a knitting-machine, the combination 75 of an annular needle bed having an opening for the yarn inside the needle bed, hooked needles movable radially in the said bed with their hooks directed outward, a revolute circular disk placed on the former one, 80 a crank-arm adapted to turn within certain limits relatively to the disk, a yarn-guide carried by the said crank-arm, and needle-operating cams carried by the said revolute disk and arranged so as to allow the needles 85 to be moved by hand to an outer inoperative and an inner inoperative position independent of said needle-operating cams, part of said cams, including an adjustable element, being adapted to move the needles to 90 an intermediate operative position when said element is properly adjusted.

3. In a knitting-machine, the combination 95 of an annular needle bed having an opening for the yarn inside the needle bed, hooked needles movable radially in the said bed, with their hooks directed outward, a revolute circular disk placed on the former one, a crank-arm adapted to turn within certain limits relatively to the disk, a yarn-guide 100 carried by the said crank-arm, a spring hook for conducting the yarn and a spring arm for stretching it, both carried by the crank-arm, and needle-operating cams carried by the said revolute disk and arranged so as to allow the needles to be moved by hand to an outer inoperative and an inner inoperative position independent of said needle-operating cams, part of said cams, including an adjustable element, being adapted to 105 move the needles to an intermediate operative position when said element is properly adjusted.

4. In a knitting-machine, the combination 110 of a central standard adjustable in length 115 and having a central opening, a circular disk carried by the said standard, said disk forming an annular needle bed, hooked needles movable radially in the said bed, with their hooks directed outward, a revolute circular 120 disk placed on the former one, a yarn-guide carried by the said revolute disk, needle-operating cams carried by the same disk and arranged so as to allow the needles to be moved by hand to an outer inoperative, 125 and an inner inoperative position independent of said needle-operating cams, part of said cams, including an adjustable element, being adapted to move the needles to an intermediate operative position when said ele 130

ment is properly adjusted, and yarn-supplying means placed at the foot of the standard.

5. In a knitting-machine, the combination 5 of an annular needle bed having an opening for the yarn inside the needle bed, hooked needles movable radially in the said bed, with their hooks directed outward, a revoluble circular disk on the former one, a 10 yarn-guide carried by the said revoluble disk, needle-operating cams projecting from the said disk and arranged so as to allow the needles to be moved by hand to an inner inoperative and an outer inoperative position 15 independent of said needle-operating cams, part of said cams, including an adjustable element, being adapted to move the needles to an intermediate operative position, and one of the needle-operating cams being adjustable in radial direction toward and 20 away from the other cams.

6. In a knitting-machine, the combination 25 of an annular needle bed having an opening for the yarn inside the needle bed, hooked needles movable radially in the said bed, with their hooks directed outward, a revoluble circular disk placed on the former one, a 30 yarn-guide carried by the said revoluble disk, needle-operating cams projecting from the said disk, and a radially adjustable needle-operating cam adapted to be placed in a position in which all the needles are inoperative.

7. In a knitting-machine, the combination 35 of an annular needle bed having an opening for the yarn inside the needle bed, hooked needles movable radially in the said bed, with their hooks directed outward, a revoluble circular disk placed on the former one, a 40 yarn-guide carried by the said revoluble disk, needle-operating cams projecting from the said disk and arranged so as to allow the needles to be moved by hand to an inner inoperative and an outer inoperative position 45 independent of said needle operating cams, part of said cams, including an adjustable element, being adapted to move the needles to an intermediate operative position when said element is properly adjusted, one of the needle-operating cams being 50 adjustable in radial direction toward and away from the other cams, and means for indicating the position of the said adjustable cam.

8. In a knitting-machine, the combination 55 of an annular needle bed, hooked needles movable radially in the said bed, with their hooks directed outward, a revoluble circular disk placed on the former one, a yarn- 60 guide carried by a driving member of said revoluble disk, and needle-operating cams carried by the said disk and arranged so as to allow the needles to be moved by hand to

an outer inoperative and an inner inoperative position independent of said needle-operating cams, part of said cams, including an adjustable element, being adapted to move the needles to an intermediate operative position when said element is properly adjusted. 65

9. In a knitting-machine, the combination 70 of an annular needle bed, hooked needles movable radially in the said bed, with their hooks directed outward, a revoluble circular disk placed on the former 75 one and provided with needle-operating means arranged so as to allow the needles to be moved by hand to an outer inoperative and an inner inoperative position independent of said needle-operating means, and including a fixed cam, and a coöperating adjustable guiding tongue adapted to move needles placed in the inner inoperative position outward upon proper adjustment of 80 said tongue.

10. In a knitting-machine, the combination 85 of an annular needle bed, hooked needles movable radially in the said bed, with their hooks directed outward, a revoluble circular disk placed on the former one and having such a shape as to allow the needles to be freely moved to an outer inoperative, an inner inoperative, or an intermediate operative position, an adjustable guiding tongue adapted to be placed in a position in 90 which it moves the needles placed in the inner inoperative position outward, and a part projecting from the revoluble disk and acting in conjunction with the guiding tongue to move the needles into the operative position. 95

11. In a knitting-machine, the combination 100 of an annular needle bed, hooked needles movable radially in the said bed, with their hooks directed outward, a revoluble 105 circular disk placed on the former one, and having such shape as to allow the needles to be freely moved to an outer inoperative, an inner inoperative, or an intermediate operative position, needle-operating cams projecting from the said disk, a flange projecting downwardly from the revoluble disk and serving as an abutment for the needles in the outer inoperative position, said flange having openings near the said cams, a 110 needle-supporting arc placed outside the said openings, and preventing the needles placed in the outer inoperative position from dropping, and means for causing the needles lying in the said outer inoperative 115 position to slide outward upon the said arc. 120
